COMBINED DENTAL TUBE SQUEEZER AND BRUSH HOLDER

Filed July 1, 1940

Inventor,
John Durin;
By his attorney,
Frederick Maynard.

UNITED STATES PATENT OFFICE

122,263

DESIGN FOR A COMBINED DENTAL TUBE SQUEEZER AND BRUSH HOLDER

John Durin, Beverly Hills, Calif.

Application July 1, 1940, Serial No. 93,375

Term of patent 7 years

To all whom it may concern:

Be it known that I, John Durin, a citizen of Latvia and resident of Beverly Hills, Los Angeles County, State of California, have invented a new, original, and ornamental Design for a Combined Dental Tube Squeezer and Brush Holder, of which the following is a specification, reference being had to the accompanying drawing, forming a part hereof.

The figure is a perspective of the holder, showing the new design thereof.

I claim:

The ornamental design for a combined dental tube squeezer and brush holder, substantially as shown.

JOHN DURIN.
